UNITED STATES PATENT OFFICE.

THOMAS SEEVERS, OF OSKALOOSA, IOWA; GRACE SEEVERS ADMINISTRATRIX OF SAID THOMAS SEEVERS, DECEASED.

EXCAVATING, DUMPING, AND SPREADING MACHINE.

Application filed October 30, 1920. Serial No. 420,717.

To all whom it may concern:

Be it known that I, THOMAS SEEVERS, a citizen of the United States, residing at Oskaloosa, in the county of Mahaska and State 5 of Iowa, have invented a new and useful Excavating, Dumping, and Spreading Machine, of which the following is a specification.

This invention relates to that class of machines sometimes known as excavating carts.

Objects of the present invention are to provide a machine which will excavate earth during the forward traveling of the machine, carry the excavated material into a 15 hopper or receptacle, transport the material to the desired point, dump the material either as a mass or by degrees, and if desired spread the dumped material or level it to provide a comparatively smooth surface. 20 Other objects are to provide a machine of the indicated character, which, after the hopper is filled with the excavated material, may be used as a carrier and dumper without having recourse to the spreading or leveling means.

More specific objects are to provide a novel means for conveying plowed earth as it is broken by the plow from the ground to a point above a hopper; and to provide improved means for positively forcing the earth, so lifted, into the hopper and then distributing it so that the hopper is filled evenly on all sides.

Further objects are to provide means whereby the element which lifts the earth may be freed from or cleaned of said earth when the machine is to be no longer used; to provide an improved spreader, and lever; and in general to effect advances in the 40 state of the art to which the present machine belongs.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawing:—

Fig. 1 is a side elevation, with parts in

section, of a machine representing an embodiment of the present invention.

Fig. 2 is a top plan view of the same.

Fig. 3 is a front elevation with parts of the frame in cross section.

Fig. 4 is a vertical transverse cross section through the central part of the machine.

Fig. 5 is a detail elevation showing part of the control means for dumping the material.

Fig. 6 is a detail view showing the means for holding the excavated material in the earth-elevating wheel and the control levers therefor.

In the drawing wherein is shown a preferred embodiment of the invention by way of illustration, the numeral 10 designates the main frame of the machine, the forward end of which is suitably fashioned so that 75 draft appliances may be hitched thereto. The present machine is well adapted to be pulled by a tractor and the frame should be constructed accordingly. Mounted upon the frame 10 is a hopper or receptacle 11 provided with cut-out sections 11^a and 11^b on opposite sides at the top thereof for a purpose to be described. This hopper or receptacle is open at the top and has its sides converging somewhat downwardly so that 85 the bottom of the hopper is of smaller area than the top. Passing through the hopper is a sleeve or housing 12 which encloses an axle. Fast to one end of the axle is a conveyer wheel 14, and loosely mounted on the 90 opposite end of the axle is a second wheel 13 of ordinary construction. The two wheels together support the cart and at the same time allow the cart to turn readily.

The elevating wheel 14 has a considerably 95 wider tread or rim than has the wheel 13 and built into this tread is an annular elevating pocket which forms an important part of the present invention. This pocket 17 is provided by a wall 15 at right angles 100 to the tread or rim of the wheel and inside the latter, in conjunction with an annular inner wall 16 which is frusto-conical in form. The chamber or pocket 17 thus formed has a depth greater than half the 105 width of the wheel rim and is of greatest width on the interior of the wheel 14, decreasing in width inwardly as the wall 15 is approached. Secured to the hopper 11 and extending through the cutaway section 11^a 110

is a scraper 18. Said scraper is bent at such an angle that its lower edge engages with the inner face of the inclined wall 16; that is, the face which is presented to the 5 pocket 17. This scraper not only engages with the wall 16 but also at its end with the straight wall 15, and is of sufficient width that its outer or free end will nicely fit the pocket at its point of least width. The 10 scraper 18, as seen in Fig. 1, also extends rearwardly relative to the vehicle so that its free end engages with the wall 15 before its lower edge engages with the wall 16.

The bottom of the hopper 11 is closed by 15 hinged doors 19 opening downwardly. Said doors are maintained in closed position by chains 20 secured to a shaft 22 mounted in brackets 21 and extending longitudinally of the machine above the hopper. As the shaft 20 is rotated by means to be described, the chains 20 will be wrapped about the shaft, thus bringing the doors 19 to closed position, or else they will be unwrapped therefrom, whereupon the doors will swing out- 25 wardly to dump the material.

The forward end of the shaft 22 mounts a hand wheel 23. A spring 24 similar to a clock spring is secured at one end to the shaft 22 and is housed within a recess provided on a ratchet disk 25 on wheel 23 and has its outer end secured to said disk. A pawl 26 is pivotally mounted upon the hopper, as indicated at 27, and has a handle 28 normally maintained in raised position by a 30 coil spring 29. The spring 29 tends to maintain the pawl in engagement with the teeth of the ratchet disk. The spring 24 tends to move the shaft 22 in such direction that the doors 19 are maintained in closed position, 35 and if there is no material in the hopper, said spring will keep said doors closed. The dumping of the load winds up the spring 24, said dumping being allowed to take place only when the pawl is swung out of engage- 40 ment with the ratchet disk. After the load is dumped, the tension of the spring returns the doors to closed position and the pawl, being spring-pressed against the ratchet, holds the disk and hence the shaft 22 in the 45 necessary position so that more excavated material may be conveyed into the cart and held therein until the time for the next dumping occurs.

Secured to the forward end of the frame 50 near the top of the hopper is an arcuate bar 30 having one or more notches therein. A hand lever 31 swings over the notch bar 30 and is normally maintained in a position almost upright by a spring 32. The lower end 55 of the lever 31 is pivoted, as indicated at 33, on the under side of frame 10, and an arm 34 is so secured to the lever 31 that forward movement of said lever lifts the free end of the arm. At said free end, a disk plow 35 is 60 mounted, said disk plow being in adjusted

position to the wheel 14 and so positioned that the plowed-up earth is thrown into the annular pocket 17. As will be noted, the disk plow 35 is set in advance of the lowest part of the wheel 14. The tendency of 70 spring 32 will be to hold the plow into the ground. When it is desired to lift the plow, as when the machine is being used to transport the excavated material, the lever 31 will be moved until its detent or dog engages 75 with a notch of the arcuate bar 30.

Secured upon the outside of the hopper and between the hopper and the wheel 14 is a plate 36 having a depending hinged leaf 37. The plate and its leaf cover the elevating pocket 17 for a distance less than half the circumference of the wheel 14. The rod 38 has a crank 39 formed near one end thereof engaging with suitable elements provided on the leaf 37 so that oscillation of said rod 80 will cause swinging of the leaf on its hinges; or, in other words, toward and from the inner face of the wheel 14. To effect this oscillation, the rod 38 is supported in bearings 41 on the underside of the frame 10, and a lever 40 is fixed at the forward end of said rod. The lower part of the leaf 37 is disposed to the rear of the lowest part of the wheel 14 and therefore also to the rear of 85 the disk plow 35.

Secured to the hopper, and extending across the top of the same in a longitudinal direction, is a bar 42 providing a support for a distributing wheel including a hub 43 and arms 44. Said arms extend between the spokes of the wheel 13 whereby the distributing wheel is turned during the advance of the machine. Said distributing wheel is designed to take the earth delivered by the elevating wheel and spread it evenly over 90 the interior of the hopper so that the earth will not pile up on the side of the hopper where the scraper 18 is provided.

Secured upon the machine to extend upwardly therefrom is an arcuate bar 45 having notches with which the detent or dog of a lever 46 is designed to engage. A rock shaft 48 is supported in bearings 47 at the rear of the machine and is secured to the lever 46 so that rocking of the lever causes 100 oscillation of said shaft. A pair of arms 49 are also secured to the rock shaft, each arm having a slot 50 at its outer end. Within 105 each slot a pin is movable, which pin connects two upright bars 51 and a slanting bar 52 with the two arms 49. The bars 51 and 52 together form a yoke or hanger frame for supporting the V-shaped spreader or leveler 54; and links 53 are provided 110 pivotally connected with the frame at one end and with the bars 51 at their outer end so as to provide with the arms 49 a parallel motion linkage. By this means the spreader or leveler, when raised or lowered 115 by lever 46, moves in straight lines.

When the disk plow engages with the soil, it will throw earth in the circular elevating pocket 17. This earth will be carried by the rotation of the wheel 14, upwardly. 5 As it is carried upwardly, the plate 36 with its leaf 37, will prevent it from falling out of the pocket. After the earth reaches a high point in the wheel, the scraper 18 will force the earth into the hopper. The angle 10 of repose of loose earth is approximately indicated by the line R, R in Fig. 1, but the rotation of the wheel in combination with the packing of the earth into the pocket caused by the disk plow, changes this angle 15 of repose until it assumes approximately the inclination of the line L, L. This change in the angle of repose effected by the constant packing of fresh earth into the circular elevating pocket is sufficient to allow the earth 20 to be carried in a more or less compact mass, upwardly until it is opposite the cutaway portion 11^a in the hopper, where the scraper cleans the pocket out. The earth travels in a continuous stream from the disk plow 25 around the semi-circumference of the pocket, into the hopper, past the scraper which also acts as a shield and prevents any of the earth from being carried around to the ground again.

30 What I claim is:

1. In a machine of the class described, a hopper, wheels supporting said hopper, one of said wheels being a material elevating wheel, an annular pocket extending inwardly from one side of the wheel and presenting a continuous unbroken passageway, a cutaway section on the upper edge of the hopper adjacent the elevating wheel, and scraping means mounted upon the hopper in said cutaway section and extending from the hopper into said pocket for cleaning the pocket of the elevated material as the machine advances.

2. In a machine of the class described, an elevating wheel having an annular pocket extending inwardly from one side thereof, said pocket presenting a continuous unbroken passageway, and scraping means fixed upon the hopper and extending into the pocket for cleaning the elevating wheel of its conveyed material at substantially the highest point in the wheel, said scraping means having an upward and rearward incline and engaging with two of the walls of 55 the pocket to scrape the pocket clean of elevated material.

3. In a machine of the class described, a hopper having a cutaway section near the top and at one side thereof, a scraping element secured upon the hopper and extending through the cutaway section, said scraper being so disposed as to extend upwardly as well as rearwardly relative to the machine, an elevating wheel upon the same side of the hopper as the scraper, an annular pocket

formed in said wheel and presenting a continuous unbroken passageway, said scraper being received within the pocket whereby material carried to the highest portion of the wheel will be removed from the pocket 70 by the scraper so as to fall through the cutaway section into the hopper.

4. In a machine of the class described, a frame, an elevating wheel mounted upon an axle journaled in the frame, said elevating 75 wheel having an annular pocket extending inwardly from the frame side thereof, said pocket presenting a continuous unbroken passageway, and a plate mounted on the frame and covering said pocket for a distance less than half the circumference of the wheel, said plate permitting material thrown into said pocket to be carried up to a high point of said wheel and also permitting access to the pocket whereby the pocket may 80 be cleaned of the material packed therein.

5. In a machine of the class described, a frame, wheels supporting said frame, one of said wheels having an annular pocket for elevating material, said pocket presenting a 90 continuous unbroken passageway, and a plate secured upon said frame and covering said pocket for a distance less than half the circumference of the wheel, said plate having a depending hinged leaf swingable away from said wheel, and control means for the hinged leaf whereby the pocket may be cleaned of the material packed therein after the leaf has been swung away from the 95 wheel.

6. In a machine of the class described, a pair of wheels supporting the frame, one of said wheels constituting an elevating wheel and having an annular pocket extending inwardly from the side thereof adjacent the 105 hopper, said pocket presenting a continuous unbroken passageway, said hopper having a cutaway section at its top adjacent the top portion of the elevating wheel, said cutaway section having a depth at least as great as 110 the width of the annular pocket, a scraping element secured upon the hopper and extending through the cutaway section into the pocket whereby material elevated in said pocket is scraped out and falls through the 115 opening provided by the cutaway section into the hopper below, and means covering the rear side of the elevating wheel so as to enclose the pocket for an extent less than half the circumference thereof.

7. In a machine of the class described, a pair of wheels supporting the frame, one of said wheels constituting an elevating wheel and having an annular pocket extending inwardly from the side thereof adjacent 125 the hopper, said pocket presenting a continuous unbroken passageway, said hopper having a cutaway section at its top adjacent the top portion of the elevating wheel, a scraping element secured upon the hopper 130

and extending through the cutaway section into the pocket, and a plate mounted upon the frame, said plate having a depending hinged leaf, and control means mounted on the frame for effecting swinging of said leaf against or away from said wheel whereby access may be had to the pocket for cleaning the same of accumulated material.

8. In a machine of the class described, the combination of a plow, a wheel having an annular elevating pocket, a scraper fixed at a high point on said machine and extending into the pocket to clear the same of elevated material, means for catching and holding the material scraped from the pocket, means for dumping the material, and means for spreading and leveling the dumped material.

9. In a machine of the class described, the

combination of a plow, a wheel having an annular elevating pocket, a plate fixed relative to the wheel and covering the rear part thereof so that a section of the pocket less than half the circumference thereof is enclosed, said plate having a hinged leaf depending therefrom, control means whereby the leaf may be moved away from the wheel, a scraper extending into the pocket at the highest point thereof, a hopper for catching and holding material scraped from the pocket, distributing means within the hopper, dumping mechanism associated with the hopper, and a spreader or leveler mounted on the machine rearwardly of the hopper and adjustable vertically.

In testimony that I claim the foregoing as my own, I have hereto affixed my signature.

THOMAS SEEVERS.
